UNITED STATES PATENT OFFICE.

FRIEDRICH WILHELM VAN PÉE, OF MAGDEBURG-SUDENBURG, GERMANY.

SAFETY DEVICE FOR WEARING-APPAREL.

1,049,783.

Specification of Letters Patent.

Patented Jan. 7, 1913.

Application filed July 13, 1910, Serial No. 571,736. Renewed November 30, 1912. Serial No. 734,427.

To all whom it may concern:

Be it known that I, FRIEDRICH WILHELM VAN PÉE, a subject of the German Emperor, and resident of Magdeburg-Sudenburg, 5 Germany, have invented certain new and useful Improvements in Safety Devices for Wearing-Apparel, of which the following is a specification.

This invention relates to an improved 10 safety-device for securing wearing apparel against theft, which has the advantage that it can be employed without the use of a key or the like.

The essence of the invention consists in 15 that the front ends of the wearing apparel can be locked by means of a clamping device in such a way that it cannot be put on, while in the casing of the clamping device an alarm device is arranged which is set 20 in action upon any attempt of an incompetent person to unlock the safety device.

The accompanying drawing shows the improved safety-device.

Figure 1 is a sectional elevation, and Fig. 25 2 a plan view, of the same, while Fig. 3 is a sectional plan on the line A—B of Fig. 1; Fig. 4 shows a detail.

In a casing 1 two axles 2 and 3 are rev- 30 olubly mounted at a suitable distance from each other, one end of said axles projecting beyond the top of the casing and carrying there each a disk 4 and 5 with numeral or letter divisions thereon. The projecting ends of said axles are thinner than their 35 inner parts, the disks being firmly pressed upon the step thus formed by means of a milled-edged nut 6 and 7. On their lower inner ends, the axles carry fixed disks 8 and 9, the circumferences of which are adapted 40 to engage with the lateral recesses 10 and 11 of a flat bolt 12 passed through an opening in the bottom of the casing, whereby said bolt is locked, it being able to be dis- 45 engaged from the disks by notches 8' and 9' provided in the latter. The outer part of the bolt is so designed that it serves as abutment 13 against the wall of the casing and forms besides a fork 14, between which 50 a lever 15 is fulcrumed, of which one arm projects beyond one end of the casing and forms there a clamping member 16. In proximity to the latter, said lever arm 15 carries an eye 17, by which it is pivoted through the medium of a pin 18 to a link 55 20 fixed to the casing at 19.

In the clamping member 21 a groove 22 is

provided, in which with a certain play a slide 23 with roughened upper surface 24 is inserted and connected with a rod 25. The latter projects into the lock casing 1 and is 60 at one end provided with an elongated slot 26 and pivoted to a double-armed lever 28 which is fulcrumed at 27. To one end of said lever 28 a short arm 29 and to the other end a long rod 30 is pivotally attached. 65 The short arm 29 projects somewhat into the casing 31 of a known alarm spring motor and is at its free end angularly bent upward for a short piece. Said end is attached to a pawl 33, which gears with a 70 ratchet wheel 32 of the spring motor and thus keeps the latter arrested. The ratchet 32 is fixed on the axle 34 of the spring motor and connected with a centrifugal regulator 35 which effects a uniform working of 75 the spring motor. On the end of the axle 34, which projects beyond the casing 31, springy hammers 36 are fixed, which project into the cavity of a bell 37 and strike against the latter when the spring motor is 80 put in gear. The disengagement of the arresting mechanism of the spring motor is effected by removal of the pawl 33 from the teeth of the ratchet wheel 32 in such a way 85 that the rod 25 is shifted in the direction of the arrow *a* shown in Fig. 3. Thereby, first the lever 28 is turned and thus the pawl 33 is brought out of gear with the ratchet wheel 32, so that then the spring motor is 90 free from the arresting gear, and the alarm 95 device is operated. Upon said movement of rod 25, a blade spring 38 arranged thereon engages by its indentation with the wall of the casing 1, whereby the rod 25 is kept in drawn-out position, so that the spring motor 100 can run off. The forward movement of rod 25 is effected in that a pull is exerted on the wearing apparel, which is clamped between the grippers 16 and 24, for instance when an attempt is made to remove the 105 wearing apparel from the grippers. Consequently the alarm device is operated as soon as an attempt is made to bring the secured wearing apparel out of connection with the safety-device. The arresting of the spring motor is effected by moving the rod 25 back, whereby the pawl 33 is again brought in gear with the ratchet wheel 32.

A disengagement of the arresting mechanism of the spring motor is further effected by a movement of the rod 30 in the direction of arrow *b* in Fig. 3, the lever 28

being thereby also turned on its fulcrum 27 and the pawl 33 brought out of gear with the ratchet wheel 32. The rod 30 is connected with a headed bolt 39, which is 5 guided in the wall of the casing 1. Between the latter and the head 40 of said bolt, a spiral spring 41 is located on the latter, while from the eye-end 42 of said bolt a chain 43 is suspended, which at its 10 other end can be connected with a hook 44 arranged on the end of lever 15. Upon a pull against the action of spring 41 being exerted on said chain 43, which is to be passed through a button-hole of the wearing apparel to be secured and by which the latter with the safety-device can be 15 suspended from a wardrobe-hook, also the rod 30 is so moved that by the same the pawl 33 is brought out of gear with the ratchet wheel 32 and the alarm device is set 20 in operation. Upon the pull on the chain 43 being ceased, the spring 41 moves the bolt 39 automatically back into its position of rest and at the same time the rod 30 25 is moved that the pawl 33 is again brought into gear with the ratchet wheel 32. An opening of the safety-device cannot be effected until the disks 5 and 9 are disengaged from the bolt 12.

30 With the aid of a pointer 45, the disks may be set to a certain numeral or letter for their being opened, so that the owner only is able to quickly remove the safety-device, for which purpose any numeral or letter on 35 the disks can be chosen and altered from time to time, as the disks 4 and 5 are movable on the axles 2 and 3 and can be turned thereon after loosening the nuts 6 and 7.

40 The improved safety-device can be also used for locking all kinds of articles, such as for instance bicycles or the like.

Having fully described my invention,

what I claim and desire to secure by Letters Patent is:—

A safety-device for locking wearing apparel, and the like, comprising in combination, a pair of clamping members, one fixed and the other movable, a casing to carry the fixed clamping member, a slide with roughened gripping surface movably arranged in the face of the fixed member, a rod fixed to said slide and arranged to lead into said casing, a blade spring with an indentation on said rod, a spring motor in said casing, means to arrest the latter by said rod, an alarm bell connected with said spring motor, means to operate said bell by the latter upon the rod being forcibly withdrawn from the motor, a headed bolt carried by the movable clamping member and adapted to project into said casing, two revolute axles in said casing each designed to project at one end from the same, a revolute notched disk keyed on each axle adapted to lock said bolt and to disengage the same at a certain position of the disks only, an adjustable numeral disk on the outer end of each axle, a nut on each axle to fix the numeral disks thereon, a pointer between said disks, a hook on the free end of said movable clamping member, a spring bolt on the end of said casing opposite to the clamping members, a chain connected to said spring bolt and adapted to be hung into said hook, and connections between said spring bolt and rod, all for the purpose set forth.

In testimony whereof I have hereunto set my hand in the presence of two subscribing witnesses.
